UNITED STATES PATENT OFFICE.

FELIX G. KAPELMAN, OF NEW YORK, N. Y.

CORNER-LOCK FOR METAL FRAMES.

1,249,416.

Specification of Letters Patent. Patented Dec. 11, 1917.

Application filed December 29, 1916. Serial No. 139,450.

To all whom it may concern:

Be it known that I, FELIX G. KAPELMAN, a citizen of the United States, residing in New York city, in the county of Bronx and

5 State of New York, have invented certain new and useful Improvements in Corner-Locks for Metal Frames, of which the following is a specification.

This invention relates in general to means 10 for locking two sections together at an angle to one another.

One of the main objects of the present invention is to provide a corner lock for locking two sections of angle irons together at 15 an angle to one another which corner lock is mainly composed of standard sheet iron angular pieces.

The present corner lock finds adaptation with bed frames as illustrated.

20 These and other features, capabilities and advantages of the invention will appear from the subjoined detail description of one specific embodiment thereof illustrated in the accompanying drawings, in which—

25 Figure 1 is a fragmental plan view showing the corner lock secured to a bed post.

Fig. 2 is a fragmental elevational view of the same.

Fig. 3 is a section along the line 3—3 of 30 Fig. 2.

Fig. 4 is a fragmental perspective of one of the parts of the lock; and Fig. 5 is a fragmental perspective of another of the parts of the lock.

35 Fig. 6 is a fragmental plan view of the part illustrated in Fig. 4; and Fig. 7 is a fragmental plan view of the part illustrated in Fig. 5.

In the embodiment illustrated there is 40 shown a bed-post and a bracket B secured to such post by a vertical pin in the usual manner. The bracket in the present instance is riveted by means of two rivets 8, 8, to the arm 9 of one of the main parts 10 of the 45 corner lock.

11 and 12 indicate, generally, the sections to be secured to one another, member 11 in this case, as shown in the drawing, being one side-rail of the bedstead. The part 10

50 of the lock, which is a bracket in form, comprises essentially a web portion 13, the arm 9 extending from one side thereof and the arm 14 extending from the other side thereof. The upper end of the web portion 13 is 55 preferably recessed at 15, as shown, and near its lower edge is secured the rivet 16 which

has a head 17 (Fig. 7) spaced from the rear face of the web portion 13 a distance substantially equal to a thickness of the sheet metal pieces being used.

To the inner upper side of the arm 14 is rigidly secured one end of the section 11 which is of angle iron construction in the present instance and has its horizontally extending portion 18 cut away adjacent to the 65 arm 14, as shown at 19, to facilitate the operation of the screw 20 about to be described.

The screw 20 has a lower screw threaded end 21 coöperating with the laterally extending arm 22 of the bracket 23 pivotally connected to the inner side of the arm 14 below the section 11. The upper end of the screw 20 is provided with a wing 24 for manipulating the same, having a flat face 25 70 below such wing 24 for coöperating with the horizontally extending arm 26 of the section 12.

The arm 26 is provided at one end with an outwardly flaring recess 27 to receive the 80 shank of the screw 20. Below the recess 27 there is provided a plate 28 which is riveted to the vertically extending arm 29 of the section 12. The upper end of the plate 28 adjacent to the arm 26, has an elongated 85 downwardly projecting finger 30, and the lower end of the plate 28 is provided with a recess 31.

In the assembling of the corner lock, the web portion 13 of the part 10 is placed 90 against the plate 28 with its arms 9 and 14 extending in the direction of the arm 26, with its recessed portion 15 thrust under the finger 30 and the rivet 16 thrust into the recess 31. Thereupon the screw 20, which 95 shall have been tilted to one side, will be rocked over so that its shank enters the recess 27, and its head 24 is disposed above the arm 26; and then the screw 20 is screwed down with its face 25 drawn tightly against 100 the arm 26.

It is obvious that various changes and modifications may be made to the details of construction without departing from the general spirit of the invention.

I claim:

1. The combination with two sections, of a corner lock for connecting said sections to one another at an angle, said lock comprising a plate member secured at substantially 110 a right angle to one of said sections, a second plate member secured to the other of

said sections and parallel therewith, said plate members being adapted to be interlocked with one another, a screw pivotally connected to said first plate member, a horizontally extending arm on the section to which the second plate member is secured, there being a recess in said arm for receiving said screw, and a head on said screw for engaging said arm when said screw is rocked into said recess so that when the screw is drawn tight it will securely anchor the plates to one another in interlocked position.

2. The combination with two sections, of 15 a corner lock for connecting said sections to one another at an angle, said lock comprising a plate member secured to each section, a rivet on the lower end of one of said plate members, a finger on the upper end of the 20 other plate member and a recess at its lower end, the finger receiving the upper edge of the first named plate member and the recess receiving the rivet of said first named plate member, and a screw pivoted to one of the 25 plates for anchoring said plate members in interlocked position.

3. The combination with two sections, of 30 a corner lock for connecting said sections to one another at an angle, said lock comprising a plate member secured to each section, the plate members being adapted to be interlocked with one another, a bracket pivotally mounted on one of said plate members, a screw screwthreadedly connected to said bracket, and a head on said screw for engaging the section to which the other plate member is connected so that when the screw is drawn tightly the plate members will be 35 securely anchored to one another in interlocked position.

4. The combination with two sections, of 40 a corner-lock comprising an interlocking tongue and groove carried by the sections for separably connecting said sections together at substantially a right-angle one to the other; and a vibrating locking-member pivoted to one section, the other adjacent right-angled section being cut-away or cham- 45

fered to permit of free vibration of the locking-member.

5. The combination with two sections, of 50 a corner-lock comprising an interlocking tongue and groove carried by the sections for separably connecting said sections together at substantially a right-angle one to the other; and a vibrating locking-member pivoted to one section, the other adjacent right-angled section being L shaped in cross-section, and being cut-away or chamfered to 55 permit of free vibration of the locking-member in the horizontal end-portion.

6. The combination with two sections, of 60 a corner-lock comprising an interlocking tongue and groove carried by the sections for separably connecting said sections together at substantially a right angle, one to the other; and a vibrating locking member pivoted to one section and fitting and locking in a slot therein, and the other coacting right-angled section being cut-away or chamfered, to 65 permit of free movement of the vibrating locking member into and out of locking position so as to permit of separation of the sections.

7. The combination with two sections, of 70 a corner-lock comprising an interlocking tongue and groove carried by the sections for separably connecting said sections together at substantially a right angle, one to the other; and a vibrating locking member pivoted to one section and fitting and locking in a slot therein, and the other coacting right-angled section being cut-away or chamfered, to 75 permit of free movement of the vibrating locking member into and out of locking position so as to permit of separation of the sections, both of the sections being of L shape in cross-section, and the slot and chamfer being in each case formed in the horizontal webs or portions of the L 80 shaped sections.

FELIX G. KAPELMAN.
